UNITED STATES PATENT OFFICE.

ADONIRAM J. COLLAR, OF YREKA, CALIFORNIA.

DITCH-GATE.

976,434.

Specification of Letters Patent. Patented Nov. 22, 1910.

Application filed January 3, 1910. Serial No. 536,067.

To all whom it may concern:

Be it known that I, ADONIRAM J. COLLAR, a citizen of the United States, residing at Yreka, in the county of Siskiyou and State 5 of California, have invented new and useful Improvements in Ditch-Gates, of which the following is a specification.

This invention relates to ditch gates.

It is the purpose of my invention to provide a gate adaptable equally to control the flow of water through canals, tunnels, ditches, flumes, etc.; to provide a gate of peculiar structure and design, and to provide a packing in combination with the gate 15 of exceptional efficiency and strength.

The invention consists of the parts, and the construction and combination of parts as hereinafter more fully described and claimed, having reference to the accompanying 20 drawings, in which—

Figure 1 is a vertical, longitudinal section of the gate as applied to a tunnel. Fig. 2 is a plan of same. Fig. 3 is a rear elevation of the curtain packing. Fig. 4 is a transverse, 25 sectional detail of a packing bar. Fig. 5 shows a modified form of curtain packing.

The embodiment of my invention as illustrated, comprises a gate A of any suitable material, so designed and constructed as to have its face concentric with a pivot or inverted U-shaped bearing 2 upon which the gate may swing to control the flow of water from the head B to a branch canal or ditch C.

When the gate is applied to a tunnel, as B, 35 its height and width are such as to conform closely to the relative dimensions of the tunnel; and to prevent leakage of water around the edges of the gate I provide packing bars or members 3 of appropriate material arranged contiguous to the vertical and the bottom edges of the gate. I prefer to construct these packing bars of triangular material and place them in such position that the hypotenuse is presented to the pressure 45 of water, and is covered with a strip of packing material 4 adapted to lap upon the surface of the gate and of the tunnel or ditch, and to protect the packing strip from abrasion and injury it is covered by a thin sheet 50 of metal or other sufficient substitute 5.

By securing the packing bar 3 to the gate A in such a manner as to allow it to have a little play, a particularly efficient packing is obtained, and therefore the bars are preferably secured to the gate by suitable bolts, or 55 the equivalent, 6, either having play in the

gate or in the bars, or both, to permit the water to press the packing member laterally against the walls of the tunnel.

To prevent leakage at the upper edge of the gate, there is employed a movable curtain-like member 7, attached in a convenient manner, as by pivot pins or bolts 8 to the roof of the tunnel B, and adapted to be thrust into snug contact against the upper 65 portions of the door.

The member 7 is cut angularly on its ends (Fig. 2), to allow the angular packing bars 3, secured to gate A, to pass upwardly without interference, and to the curtain member is suitably fastened a strip of flexible packing material 9 closely following the exposed edges of the curtain and adapted to bear upon the gate and tunnel surfaces, a sheet of packing 10 being also secured to 75 the upper plane of the curtain 7, preventing leakage above the gate.

It will thus be seen that the gate is thoroughly provided at all points where leakage is likely to occur, with a packing device that is reliable, simple and perfectly protected, and for the purpose of reducing the resistance of the gate during adjustment, it is provided adjacent to its vertical edges, with antifriction rollers 11 adapted to bear upon 85 the walls of the canal.

Under certain conditions it is advantageous to employ a curtain packing such as shown in Fig. 5, comprising a triangular bar 12, loosely mounted on bolts 13 secured in the tunnel roof, and having one concave face bearing upon the gate A. Upon the wide side of the bar is laid a packing strip 14 covered and protected by a suitable facing 15 fastened to the bar.

When subjected to pressure the various packing members are forced into water-tight contact with the gate and walls, and yet do not bind the gate or interfere with its adjustment; and further the rollers 11 always maintain the gate equidistant between the walls, thus preventing the gate shifting sideways tightly against either wall.

Having thus described my invention, what I claim and desire to secure by Letters Patent is—

1. The combination with a water system, of a pivoted adjustable gate, packing members mounted thereon contiguous to its edges, and a packing curtain mounted independently of but adapted to bear upon the gate.

2. A curved gate for waterways, a pivot upon which it may swing, and a packing device of curtain-like form mounted independently of but adapted to bear upon the curved face of the gate.

3. A gate for waterways, a pivot upon which it may swing, the gate having a face curved concentrically with the pivot, packing bars of triangular cross-section laid upon

the face, and means whereby the packing bars are loosely secured to the gate.

In testimony whereof I have hereunto set my hand in the presence of two subscribing witnesses.

ADONIRAM J. COLLAR.
